UNITED STATES PATENT OFFICE.

LARS O. GRONDAHL, OF PITTSBURGH, AND LESTER E. SPRAY, OF WILKINSBURG, PENNSYLVANIA, ASSIGNORS TO THE UNION SWITCH & SIGNAL COMPANY, OF SWISSVALE, PENNSYLVANIA, A CORPORATION OF PENNSYLVANIA.

ELECTRICAL APPARATUS.

Application filed December 27, 1921, Serial No. 525,098. Renewed February 18, 1925.

To all whom it may concern:

Be it known that we, LARS O. GRONDAHL and LESTER E. SPRAY, citizens of the United States, residing at Pittsburgh and Wilkinsburg, respectively, in the county of Allegheny and State of Pennsylvania, have invented certain new and useful Improvements in Electrical Apparatus, of which the following is a specification.

10 Our invention relates to electrical apparatus, and particularly to apparatus for supplying current of one characteristic or another to an energy-consuming device. One particular form to which the invention is 15 well adapted, and the form which we will describe herein, is that of polarity reversing apparatus, by which we mean apparatus for supplying current of one polarity or the other, or in the case of alternating current 20 one instantaneous relative polarity or the other to an energy-consuming device. It is understood, however, that the invention in its broader aspects is not limited to apparatus for this specific purpose.

25 One feature of our invention is the provision of apparatus for the purpose set forth having no moving parts, the results being accomplished by means of electrical valves or relays which depend for their action on 30 substances the electrical resistance of which varies with variations in temperature.

The present invention is especially well adapted for use in railway signaling systems, although it is not limited to this 35 specific use.

We will describe two forms of apparatus embodying our invention, and will then point out the novel features thereof in 40 claims.

In the accompanying drawings, Fig. 1 is a diagrammatic view showing a portion of a 45 railway signaling system including one form of polarity reversing apparatus embodying our invention. Fig. 2 is a view showing a modified form of polarity reversing apparatus embodying our invention which may be substituted for the corresponding apparatus in the signaling system shown in Fig. 1.

Similar reference characters refer to similar parts in each of the views.

Referring first to Fig. 1, the reference characters D and D^a designate the track rails of a railway along which traffic normally moves in the direction indicated by the ar-

row, and which rails are divided by suitable 55 means, such as insulated rail joints 2, to form electrically isolated track sections A—B, B—C, etc.

The rear section B—C is provided with a signal S located adjacent the entrance end 60 of the section and comprising, as here shown, three electric lamps, G, Y, and R, adapted when lighted to indicate "proceed," "caution" and "stop," respectively. This signal is controlled by suitable apparatus 65 which is responsive to reversals of polarity of current as well as to the presence and absence of current, and such apparatus is in turn supplied with current of one polarity or the other from the track rails of section 70 B—C. The apparatus for the immediate control of signal S forms no part of our present invention, and is fully described and claimed in a co-pending application by Lars O. Grondahl, filed on the ninth day of 75 February, 1922, Serial No. 535,194, for railway signaling. Briefly described, this apparatus comprises two electron tubes J^a and J^b, each having a filament 13, a grid 14, and a plate 15. The filaments 13 are constantly 80 heated by the secondary 16 of a transformer T^c through a circuit which will be obvious from the drawing, and the primary 17 of transformer T^c is connected with a transmission line 4 which is constantly supplied 85 with signaling current by a generator 18. Each electron tube is provided with a grid circuit which is energized from the secondary of a transformer F, the primary of which is connected across the rails of section 90 B—C at the entrance end of the section.

The electron tube J^a is provided with a plate circuit which passes from the left-hand terminal of the secondary 19 of transformer T^c, through the proceed lamp G, 95 plate, and filament of tube J^a, and common return wire 20, to the middle point of secondary 19. The electron tube J^b is provided with a similar plate circuit which passes from the right-hand terminal of transformer secondary 19, through the caution lamp Y, the plate, and filament of tube J^b, and the common return wire 20, to the middle point of secondary 19. At any given instant the polarities of the grids 14, of the 100 two tubes J^a and J^b, are the same, whereas, at any given instant, the polarities of the plates 15, of these tubes, are opposite. It

follows that when current of one relative polarity is supplied to transformer F by the track rails of section B—C, the plate circuit for tube J^a is conductive, while the 5 plate circuit for tube J^b is non-conductive, so that, under such condition, the proceed lamp G will be lighted and the caution lamp Y will be extinguished. When the relative polarity of the current in the track circuit 10 for section B—C is reversed, however, the plate circuit for tube J^b will be conductive, and the plate circuit for tube J^a will be non-conductive, so that the caution lamp Y will be illuminated and the proceed lamp G will 15 be extinguished.

The stop lamp R is connected with secondary 21 on transformer T^c, and this lamp is provided with a shunt which includes the 20 thermo-sensitive element 6 of a thermo-sensitive relay K^d; the heating element 7 of which is connected with the secondary of transformer F. Relay K^d has a negative 25 temperature coefficient, that is, the resistance of the thermo-sensitive element 6 decreases with increase of temperature. It follows 30 that when track section B—C is unoccupied, so that heating element 7 is supplied with current, the resistance of the shunt around the stop lamp R is so low that this lamp is extinguished, but when section B—C is occupied by a car or train, so that the supply 35 of current to the heating element 7 is discontinued, the resistance of element 6, and, consequently, the resistance of the shunt around lamp R, is increased to such a value that this lamp becomes lighted.

Alternating current of one instantaneous relative polarity or the other is supplied to the track rails of section B—C by a secondary 40 3 on a transformer T^b the primary of which is connected with the transmission line 4. The middle point of secondary 3 is connected with one track rail D by a wire 5, while the two outer terminals of this 45 secondary are connected with the other rail D^a, so that this secondary 3 constitutes in effect two sources of current reversely connected with the rails of section B—C. Interposed between the left-hand terminal of secondary 3 and rail D^a is the thermo-sensitive 50 element 6 of a relay or valve K^a, and interposed between the right-hand terminal and rail D^a is the thermo-sensitive element 6 of another relay or valve K^b. Relay K^a has 55 a positive temperature coefficient, that is, the resistance of its element 6 increases with increase of temperature, while relay K^b has a negative temperature coefficient, that is, the resistance of its element 6 decreases with 60 increase of temperature. The heating element 7 of relay K^a is connected with a secondary 8 of a transformer E^b, and the heating element 7 of relay K^b is connected with another secondary 8^a on the same transformer. The primary 9 of this transformer 65

is connected with a secondary 10 on transformer T^b, and the flow of current in the circuit is governed by a thermo-sensitive relay K^e having a negative temperature coefficient, the thermo-sensitive element of 70 which is included in the circuit of primary 9, and the heating element of which is connected with the track rails of section A—B. These rails are supplied with current by secondary 11 of a transformer T^a. 75

The operation of the pole-changing apparatus is as follows:

When track section A—B is unoccupied, the resistance of relay K^e is low, so that current of considerable value flows in the primary 9 of transformer E^b, with the result that relays K^a and K^b are energized. The resistance of relay K^a is then high and that of relay K^b is low, so that current is supplied to the track rails of section B—C from 80 the right-hand half of transformer secondary 3, the instantaneous relative polarity of this current is such as to cause lamp G of signal S to be lighted. When section A—B is occupied by a car or train, however, the resistance of relay K^e is maximum, so that a minimum amount of current is supplied to primary 9 of transformer E^b, and relays K^a and K^b are then de-energized. Under this condition, the resistance of relay K^a is low and the resistance of relay K^b is high, so that current is supplied to the rails of section B—C by the left-hand half of transformer secondary 3, and the instantaneous relative polarity of this current is, 85 of course, opposite to the instantaneous relative polarity of the current supplied by the right-hand half of secondary 3; the caution lamp Y of signal SC is then lighted, and the proceed lamp G is extinguished. 90

Referring now to Fig. 2, the apparatus here shown is similar to that shown in Fig. 1 except that both thermo-sensitive relays K^a and K^b have negative temperature coefficients. Current is at times supplied to the 110 heating element 7 of relay K^a from secondary 10, the circuit for which also includes the thermo-sensitive relay K^e and the primary 9 of transformer E^b. The secondary 8^a of transformer E^b is connected in series 115 with the heating element 7 of relay K^b and a secondary 12 on transformer T^b, the two secondaries 12 and 8^a being connected in such manner that they oppose each other. When section A—B is occupied by a car or train, the resistance of relay K^e is high, so that a minimum amount of current is supplied to primary 9 and heating element 7 of relay K^a, with the result that relay K^a is de-energized. Secondary 12 then supplies current to heating element 7 of relay K^b so that 120 this relay is energized, and, consequently, current is supplied to track section B—C by the right-hand half of secondary 3. When section A—B is unoccupied, however, re- 125

- lay K^e is energized, so that a maximum amount of current is supplied by secondary 10 to primary 9 and the heating element of relay K^a , whereby this relay is energized. 5 The current induced in the secondary 8^a of transformer E^B then neutralizes the current supplied by secondary 12, so that relay K^b is de-energized. Current is then supplied to section B—C from the left-hand half of 10 transformer secondary 3.
- Although we have herein shown and described only two forms of apparatus embodying our invention, it is understood that various changes and modifications may be 15 made therein within the scope of the appended claims without departing from the spirit and scope of our invention.
- Having thus described our invention, what we claim is:
- 20 1. Polarity controlling apparatus comprising two sources of current reversely connected with an energy-consuming device, thermo-sensitive relays interposed in such connections, and means for supplying current to said relays.
- 25 2. Polarity controlling apparatus comprising two sources of current reversely connected with an energy-consuming device, two thermo-sensitive relays each having a 30 negative temperature coefficient interposed between said device and said two sources respectively, and means for supplying current to one or the other of said relays.
- 35 3. In combination, two sections of rail-way track, two sources of current reversely connected with the rails of the rear section, thermo-sensitive relays interposed between said sources and said rails, and means governed by traffic conditions in the forward 40 section for controlling the energization of said relays.
4. In combination, two sections of rail-way track, two sources of current reversely connected with the rails of the rear section, two thermo-sensitive relays each having a negative temperature coefficient interposed between said track rails and said two sources respectively, and means controlled by traffic conditions in the forward section for supplying current to one of said relays or the other according as the forward section is occupied or unoccupied.
5. In combination, two sections of rail-way track, two sources of current reversely connected with the rails of the rear section, thermo-sensitive relays interposed between said sources and said rails, a track circuit for the forward section including a third thermo-sensitive relay, and means controlled by said third relay for governing the supply of heating current to the first two relays.
6. In combination, a plurality of different sources of current connected with a current-consuming device, and thermo-sensitive relays interposed in the connections between said sources and said device.
7. In combination, a plurality of sources of current displaced in phase and connected with a current consuming device, and thermo-sensitive relays interposed in the connections between said sources and said device.
8. In combination, two sections of rail-way track, two sources of alternating current displaced in phase and connected with the rails of the rear section, thermo-sensitive relays interposed between said sources and said rails, and means governed by traffic conditions in the forward section for controlling the energization of said relays.

In testimony whereof we affix our signatures.

LARS O. GRONDAHL.
LESTER E. SPRAY.
